OFFSET BENDER

Alexander G. Sadler, Overland Park, Kans.

Application June 18, 1958, Serial No. 742,937

3 Claims. (Cl. 153—39)

This invention relates to improvements in tools or machines for bending metal pipe, bars and the like, and more particularly to a tool or machine for making bends and offsets in rigid electrical conduit, metal pipe or tubing by simultaneously bending opposite end portions thereof.

The principal objects of the present invention are to provide a metal conduit bending machine with spaced stationary abutments on a base cooperating with spaced movable abutments on a pivoted platform whereby a rigid metal conduit is engaged by the abutments to make accurate offsets in the conduit in response to rotary movement of the platform; to provide such a bending machine wherein the abutments are adjustable on the base and platform to alter the relative positioning and the offset performed thereby; to provide such a bending machine in which all adjustments and manipulations of the work are made from the top thereof; to provide such a bending machine with extensible power means for pivoting the platform and effecting the bend in the conduit; to provide such a conduit or metal pipe bending machine that is economical to manufacture and that is efficient in use for quickly, easily and accurately making bends and offsets of various sizes without danger of flattening thin wall conduits or tubing; and to provide such a bending machine wherein the parts are simple in form and of rugged design and by using a few interchangeable parts the one machine will serve for a wide range of work both as to size of bends and kind of pipe or rod.

Other objects and advantages of this invention will become apparent from the following description taken in connection with the accompanying drawings, wherein are set forth by way of illustration and example certain embodiments of this invention.

Fig. 1 is a plan view of the bending machine with the parts moved to bend an offset in conduit.

Fig. 2 is a side elevation of the bending machine.

Fig. 3 is a transverse sectional view through the bending machine on the line 3—3, Fig. 1.

Fig. 4 is a transverse sectional view through the bending machine on the line 4—4, Fig. 1.

Referring more in detail to the drawings:

1 designates a rigid base member or plate having an elongate central portion 2 terminating in end portions 3 and 4 arranged in angular relation thereto whereby said end portions are in offset parallel relation to each other.

The base member is preferably of cast metal and includes a horizontal wall 5 having depending side walls 6 with lower edges 7 adapted to rest on a suitable table or other support whereby the upper face 8 of the wall 5 is substantially in a horizontal plane. An upstanding bearing post or pivot pin 9 is arranged on the wall 5 midway between the end portions 3 and 4 whereby said post extends upwardly from the face 8 of the base member. The post 9 is preferably cylindrical and fixed to the base, and in the illustrated structure has a threaded shank 10 of reduced size extending through a hole 11 in the wall 5 with a nut 12 threaded on the lower end of said shank to draw a shoulder 14 on the lower end

2

of the post into engagement with the face 8 of the base. Bearing plates or washers 15 and 16 are sleeved on the post in superimposed relation with the lower plate 15 resting on the upper face 8 of the base member. A platform or rotary member 17 preferably in the form of a circular disc has an axial bearing opening 18 to receive the post 9 whereby the platform is removably and rotatably mounted thereon, with the bottom surface 19 of said platform engaged with the upper plate 16. The platform 17 is sleeved on the post whereby said platform may be lifted from the post for servicing or for facilitating transportation of the machine.

Abutment members or brackets 20 and 21 are adjustably mounted on the platform 17 in oppositely facing relation. Each of said abutment members preferably are of the same structure, and in the illustrated structure, are substantially L-shaped with side edges 22 and 23 of one leg 24 being parallel and slidably engaged between pairs of spaced rails 25 and 26 that are upstanding from the upper face 27 of the platform 17, with the bottom face 28 of said abutment members resting on the upper face of said platform. The pairs of rails 25 and 26 are parallel and are spaced on opposite sides of a diameter of the platform, as illustrated in Fig. 1, whereby the other legs 29 of each of said abutment members extend beyond said diameter. The legs 29 each have recesses 30 extending therein from the ends of the respective legs to form a yoke-like structure with vertically aligned apertures 31 extending therethrough to mount pins 32 to pivotally mount grooved contact pieces or shoes 33. The contact pieces 33 are preferably oval in shape, with grooves 33' in the sides thereof, with the radius of the grooves of suitable size relative to the radius of the conduit to be bent to properly receive and engage said conduit. The pins 32 are preferably in a vertical diametric plane relative to the platform 17 whereby the grooved portion of the contact members or shoes 33 adapted to engage a conduit 34 to be bent are on opposite sides of said plane relative to the legs 24 of the abutment members. The platform 17 has spaced rows of threaded apertures 35 between the rails 25 and 26, and the abutments 20 and 21 have corresponding spaced rows of apertures 36 arranged whereby pairs of said apertures can be registered with the threaded apertures 35 for receiving fastening devices such as screws 37 for securing the abutments in selected adjusted position. This provides an adjustment whereby the contact members or shoes 33 may be selectively moved inwardly or outwardly relative to the axis of the post 9 to vary the bend, as later described.

Upstanding brackets or abutment members 38 and 39 are adjustably mounted on the end portions 3 and 4 of the base 1 respectively in oppositely facing relation, with bottom faces 40 of said brackets engaging the upper faces of the base. Each of the brackets has an end 41 engaging an upstanding rail 42 on the remote side of the respective end portions 3 and 4, with the other ends 43 of said abutment members 38 and 39 extending from the opposite sides of the respective end portions and terminating substantially in a vertical plane extending through the axis of the platform 17 whereby the bracket members 38 and 39 are disposed on opposite sides of said platform, as illustrated in Fig. 1. The ends 43 of the brackets 38 and 39 are recessed or yoke-shaped to receive conduit contact members or shoes 44 that are pivotally mounted on pins 45 extending vertically through the yoke-shaped ends 43 of the brackets 38 and 39. The contact members or shoes 33 and 44 are each pivotally mounted on axes parallel to the axis of the post 9, and each has grooves in the side faces whereby when a conduit is engaged with said grooves at the bottoms thereof the conduit is in a plane perpendicular to the axis of the post 9. The

grooves 45 in the sides of the shoes 44 preferably extend therearound whereby the shoes may be removed and turned to present a different conduit-engaging surface for different sizes or to increase the wear of the shoes.

The end portions 3 and 4 have spaced rows of threaded apertures 46 and the brackets 38 and 39 have apertures 47 whereby the brackets may be selectively moved to adjust their spacing toward or away from the axis of the post 9, and the apertures 47 aligned with the apertures 46 and suitable fastening devices such as screws 48 inserted therein to secure the brackets in selected adjusted position.

The conduit 34 may be placed in the machine in engagement with the shoes 44 and extending between the shoes 33. Then, by rotation of the platform 17 in a counterclockwise direction (Fig. 1), the shoes 33 are engaged with the conduit and further rotation will bend the conduit to effect an offset therein. If the shoes of each pair are set at equal distances from the axis of the post 9, the offsets will be made and the end portions of the conduit will have exact parallel alignment. It is preferable that the platform 17 be rotated by power means. In the illustrated structure, an extension 49 extends laterally from the end portion 4 of the base with suitable ribs 50 to reinforce same. The extension has an ear 51 to which is pivotally connected by a pin 52 an extensible member 53, the other end of the extensible member being pivotally connected as by a pin 54 with a lug 55 secured to the rotor 17. In the illustrated structure, there are a plurality of holes 56 adjacent the periphery of the platform, and the lug 55 has a flange 57 extending thereover and selectively registered with pairs of holes 56 whereby fastening devices 58 secure the lug in selected adjusted position and the limit of the extension of the extensible member 53 is the limit of the bending movement of the platform 17 thereby limiting the offset placed in the conduit. In the illustrated structure, the extensible member 53 is a hydraulic ram with a cylinder 59 having one end connected to the ear 51, with a piston rod 60 extending a piston 61 through the other end 62 of the cylinder and pivotally connected to the lug 55. The ram is preferably of the single-acting type, with a spring 63 sleeved on the piston rod 60 and having one end engaged with a piston 61 to urge the ram into contracted position. A pressure hose 64 is connected to the cylinder adjacent the end toward the extension 49, with the other end communicating with a pump 65 for supplying fluid pressure to the extensible member to effect extension of same. A suitable valve 66 is arranged on the pump whereby the fluid can be bled from the cylinder to a conduit 67 communicating with a reservoir (not shown) whereby the spring can contract the ram. The pump 65 is preferably operated by a handle 68 to supply the fluid pressure to extend the ram and effect bending rotation of the platform and shoes thereon to bend the conduit.

By moving the lug 55 to the right on the platform 17, the effective bending rotation of the platform is increased, thereby increasing the bend or offset in the conduit or pipe being bent. Also, moving the abutment members 20 and 21 inwardly toward the post 9 will reduce the spacing between the parallel ends of the conduit. Moving the abutment members 20 and 21 outwardly relative to the post will increase the spacing between the parallel ends of the conduit. All adjustments of the brackets or abutments for moving the shoes are made from the top of the machine, and by removing the pin 54 to disconnect the piston rod from the lug 55, the platform, together with the structure thereon, can be raised and removed from the post 9. While conduit, pipe and the like may be bent in various offsets, single bends may also be made up to 90 degrees by removing the bracket 38 whereby the conduit is engaged only by the shoes 33 on the platform and the shoe 44 carried by the bracket 39. Also, for offsets larger than are feasible in use of a given size machine, a single bend may be made and the work piece turned over and positioned to complete the bending in the usual way.

It is to be understood that while I have illustrated and described one form of my invention, it is not to be limited to the specific form or arrangement of parts herein described and shown except insofar as such limitations are included in the claims.

What I claim and desire to secure by Letters Patent is:

1. A conduit and tubing bending machine comprising, an elongate base plate having a center portion and oppositely extending offset parallel end portions, a bearing post extending from the center portion of the base plate substantially midway of said end portions, a platform rotatably mounted on said bearing post, a pair of movable brackets on said platform in diametrically opposite and in oppositely facing relation, stationary brackets on the end portions of the base plate in oppositely facing relation to the respective adjacent bracket on the platform, bending shoes pivotally mounted on each of said brackets for pivotal movement on respective axes that are parallel to the bearing post axis, all of said shoes being in a single plane perpendicular to the axis of rotation of the platform, said shoes having grooved faces for engaging a conduit to be bent, said shoes being on the facing portions of the respective movable brackets and stationary brackets whereby a conduit to be bent is placed between the shoes of the brackets on the platform and opposite end portions are engaged on opposite sides by shoes on adjacent movable and stationary brackets, and an extensible member having one end pivotally connected to the base plate and another end pivotally connected to the platform adjacent the periphery thereof for rotating said platform to move the shoes on the brackets of the platform toward the adjacent stationary shoes on the brackets on the end portions of the base plate to bend the conduit therebetween in response to extension of said extensible member.

2. A conduit and tubing bending machine comprising, a base plate, an upstanding bearing post on the base plate substantially midway thereof, a platform rotatably mounted on said bearing post, a pair of brackets on the platform in diametrically opposite relation, spaced pairs of rails in parallel relation on the platform and engaged by said brackets and defining paths for movement of the brackets toward and away from the axis of rotation of the platform for adjusting the spacing therebetween, means securing the brackets to the platform in selected position, movable shoes mounted on facing portions of said brackets, a stationary bracket on the base plate at one side of the platform, means securing the stationary bracket to the base plate at selected spacing from the adjacent movable shoe, shoes mounted on the stationary bracket at the adjacent end thereof, said shoe on the stationary bracket engaging a conduit to be bent and cooperating with the adjacent movable shoe to engage opposite sides of a conduit whereby a conduit to be bent is placed between the movable shoes and opposite sides thereof engaged by adjacent movable and stationary shoes, an hydraulic extensible member, means pivotally mounting one end of said hydraulic extensible member on the base plate, a lug adjustably mounted on the platform adjacent the periphery thereof, means pivotally connecting the other end of the hydraulic extensible member to the lug whereby extension of the extensible member rotates the platform and moves the movable shoes toward the adjacent stationary shoe to bend a conduit therebetween.

3. A conduit and tubing bending machine comprising, a base plate having a center portion and oppositely extending offset parallel end portions, an upstanding bearing post on the center portion of the base plate substantially midway of said end portions, a platform rotatably mounted on said bearing post, a pair of brackets on the platform in diametrically opposite relation, spaced pairs of rails in parallel relation on the platform and engaged by said brackets and defining paths for movement of the brackets toward and away from the axis of rotation of the platform for adjusting the spacing therebetween,

means securing the brackets to the platform in selected position, movable shoes pivotally mounted on facing portions of said brackets, said movable shoes having grooved faces for engaging a conduit to be bent, stationary brackets on the end portions of the base plate in oppositely facing directions, means securing the stationary brackets to the base plate end portions at selected spacing from the adjacent movable shoes, shoes pivotally mounted on the respective stationary brackets at the adjacent ends thereof, said shoes on the stationary brackets having grooved faces for engaging a conduit to be bent and cooperating with the adjacent movable shoe to engage opposite sides of a conduit whereby a conduit to be bent is placed between the movable shoes and opposite sides thereof engaged by adjacent movable and stationary shoes, an hydraulic extensible member, means pivotally mounting one

5 end of said hydraulic extensible member on the base plate, a lug adjustably mounted on the platform adjacent the periphery thereof, means pivotally connecting the other end of the hydraulic extensible member to the lug

10 whereby extension of the extensible member rotates the platform and moves the movable shoes toward the adjacent stationary shoes to bend a conduit therebetween.

5 end of said hydraulic extensible member on the base plate, a lug adjustably mounted on the platform adjacent the periphery thereof, means pivotally connecting the other end of the hydraulic extensible member to the lug

10 whereby extension of the extensible member rotates the platform and moves the movable shoes toward the adjacent stationary shoes to bend a conduit therebetween.
